[57] ABSTRACT

The disclosure herein describes a rug hooking needle consisting of an elongated bar, a needle member fixed to a forward end of the bar, a shuttle member mounted for reciprocated movement on the bar, a looper member having one end attached to the shuttle member and the opposite end slidably received through the needle member, a presser member slidably mounted to the elongated bar and extending longitudinally thereof, and means for adjusting the relative position of the presser member to the bar and to the shuttle member. This adjustment of the presser member enables one to vary the distance between the fabric-contacting portion of the presser member and the fabric-penetrating portion of the looper member whereby the yarn penetration in the fabric is varied accordingly.

RUG HOOKING NEEDLE

FIELD OF THE INVENTION

This invention relates to hooking needles especially adapted for working rugs or mats of the type having a base of suitable fabric through which a material is worked in the form of loops.

BACKGROUND OF THE INVENTION

This type of hooking needles is well known and may be found described, for example, in U.S. Pat. Nos. 1,605,711 and 1,941,346 issued to J. E. Garrett, respectively on Nov. 2, 1926 and Dec. 26, 1933, and in a more recent U.S. Pat. No. 3,714,915 issued Feb. 6, 1973 to J. J. Montell et al.

In the hooking needles described in these patents, the variation of the yarn penetration in the fabric is accomplished by adjusting the relative position of the yarn-penetrating looper to the shuttle member. In these hooking needles the presser member, which comes in contact with the fabric base, is integrally mounted to the shuttle member.

STATEMENT OF THE INVENTION

It is an object of this invention to provide a novel hooking needle for working rugs or mats where the variation of the yarn loops is accomplished by varying the position of the presser member relative to the shuttle member.

The invention therefore relates to a hooking needle which comprises: an elongated bar having a handle attached at one end thereof; a needle member fixed to the opposite forward end of the bar, the needle member defining an open-ended enclosure having a yarn-receiving passage and a looper-receiving passage extending longitudinally therethrough, the needle member including a fabric-penetrating portion frontwardly extending in the longitudinal axis of the bar; a shuttle member mounted to the bar for reciprocating movement thereon between the handle and the needle member; an elongated looper member having one end attached to the shuttle member and the opposite forward end slidably received in the looper-receiving passage of the needle member; a presser member slidably mounted to the elongated bar and extending longitudinally thereof, the presser member having a forward portion adapted to rest against the fabric being hooked; and means for adjusting the relative position of the presser member to the bar and to the shuttle member to thereby vary the relative position of the forward end of the presser member to the forward end of the looper member whereby the yarn penetration in the fabric may be varied.

In one preferred form of the invention, the means for adjusting the presser member consists of: a coupling member surrounding a portion of the presser member and a portion of the elongated bar, and releasable fastening means for fixing the coupling member to the said portion of the presser member.

In another preferred form of the invention the releasable fastening means cooperate with the walls of an elongated slot provided longitudinally in the elongated bar to limit the reciprocating movement of the shuttle member.

In another form of the invention, the needle member is permanently fixed to the elongated bar.

BRIEF DESCRIPTION OF THE DRAWINGS

Other objects, purposes and characteristic features of the present invention will be in part obvious from the accompanying drawings, and in part pointed out as the description of the invention progresses. In describing the invention in detail, reference will be made to the accompanying drawings, in which like reference characters designate corresponding parts throughout the several views, and in which:

FIG. 1 is an elevational view of an embodiment of a hooking needle constructed in accordance with the teachings of the present invention;

FIG. 2 is a bottom view, showing the means for adjusting the presser member;

FIG. 3 is a plan view, showing in part the hooking needle illustrated in FIG. 1;

FIG. 4 is a cross-sectional view taken along lines 4-4 of FIG. 1;

FIG. 5 is a cross-sectional view taken along lines 5-5 of FIG. 1; and

FIG. 6 is a cross-sectional view taken along lines 6-6 of FIG. 1.

DESCRIPTION OF PREFERRED EMBODIMENT

In these drawings illustrating a preferred embodiment of the invention, there is shown a hooking needle generally designated by reference numeral 10. The needle comprises an elongated bar member 12 having at one end 12a thereof a handle 14, and at the other end 12b thereof a needle member 16. The needle 10 further includes a shuttle member 20 mounted to the bar 12 for reciprocating movement thereon between the handle and the needle member. An elongated looper member 22 has one end 22a attached to the shuttle member 20 and the other end 22b slidably received in the needle member 16.

In accordance with the present invention, the needle 10 further includes an adjustable presser member 24 which has one end 24a, received within the shuttle member 20 and suitably mounted to the bar 12, and a forward end 24b which has a downwardly projection adapted to contact the fabric base to be worked.

The bar 12 is an elongated member made of rigid material, the rear end 12a of which is fixedly received in a correspondingly-shaped opening provided in the handle 14. The front end 12b of the bar has on each of its side edges a recess to receive therein in a fixed manner, such as by welding, the lower ends of the side walls of the needle member 16. The intermediate portion of the bar 12 includes an elongated slot 30, the function which will hereinafter be described.

The needle member 16 is an open-ended enclosure with opposite side walls 32 and 34 to which is internally fixed an intermediate partition 36 (see FIG. 6) defining in the enclosure an upper yarn-receiving passageway 38 and a lower looper-receiving passageway 40. The needle member 16 terminates with a pointed fabric-penetrating portion 42 projecting frontwardly in the longitudinal direction of the bar 12.

Shuttle member 20 is a metal member which includes a short rear leg portion 44 and a long front leg portion 46 inter-connected by a web portion 48 extending over the bar 12. The short leg portion 44 has an aperture for slidably receiving the bar 12 therethrough. The leg portion 46 includes an aperture 47 to slidably receive therethrough bar 12, presser member 24 and looper

member 22 (see FIG. 5). The leg portion 46 is sufficiently long to facilitate manual gripping thereof.

Looper member 22 is an elongated metal member, preferably constructed of spring steel, and is resilient. Its rear end 22a is fixed to the web portion 48 of the shuttle member by suitable fastener means, such as screw 50. The front end 22b of the looper is slidably received in passageway 40 of the needle member 16.

An important feature of the present invention is that the presser member 24 is made to be adjusted relative to the elongated bar 12 as well as to the shuttle member 20. A coupling member 52, in the form of an elongated U-shaped channel extending between the leg portions 44 and 46, surrounds the end portion 24a of the presser member 24 and an intermediate portion of the bar 12. A releasable fastener, such as screw 54, threadedly engages the end portion 24a of the presser and its shank portion end is sufficiently long so that its threaded end may protrude presser 24 and be received in slot 30 of the bar 12. Tightening screw 54 causes contacting engagement of a washer 58 with the inwardly projecting surfaces 58 and 60 of the U-shaped coupling member 52 (see FIG. 4). Therefore, the adjustment of the distance between the fabric-contacting portion 24b of the presser member and the shuttle member 20 consists in loosening fastener 54 to release the tight engagement between the washer 56 and surfaces 58 and 60 of the coupling member and in manually displacing the presser member 24 in the longitudinal plane of the bar. Once the adjustment is set, fastener 54 is tightened to form one movable unit that includes the shuttle member 20 (which also carries the looper member 22), the presser member 24 and the coupling member 52.

The reciprocating movement of the shuttle member on the bar 12 may be limited by having the rear leg portion 44 contacting the handle 14 and the front leg portion contacting the rear edges of the open-ended enclosure 16 or by having the treaded end of the fastener 54 contacting the opposite extremities 30a and 30b of the slot 30.

OPERATION OF THE INVENTION

First, the hooking needle is set for a desired loop length of material in the fabric base. This is accomplished by adjusting the position of the fabric-contacting portion 24b of the presser member relative to extremity 22c of the looper member 22; the greater the distance separating portion 24b from extremity 22c, the longer would be the loop of material formed in the fabric base since the penetration of the looper member would be greater. Once this adjustment is made, screw 54 is tightly fastened causing surfaces 58 and 60 of coupling member 52 to be squeezed between washer 56 and end 24a of the presser thereby preventing further movement between the presser 24 and the shuttle member 20 and allowing these members to move together during the reciprocating movements. Yarn is introduced in the yarn-receiving passage 38 of the needle member 16. The needle member 16 is positioned vertically over the undersurface of a fabric base and the pointed end 42 of the needle is forced through the fabric until the front edges of the sidewalls 32 and 34 of the open-ended enclosure. Then, shuttle member 20 is downwardly pushed thus engaging the yarn and holding it into a loop while simultaneously retracting the pointed end 42 upwardly from the fabric until the leg portion 46 of the shuttle member contacts the needle

member 16 or, in cases where the extremities of the slot 30 act as stoppers, until screw 54 engages the extremity 30b of the slot. This reciprocating movement is repeated thereby progressing the hooking operation.

Although the invention has been described above in relation to a specific form of the invention, it will be evident to the man skilled in the art that it may be refined and modified in various ways. It is therefore wished to have it understood that the present invention is not limited in interpretation except by the terms of the following claims.

I claim:

1. A hooking needle comprising: an elongated bar having a handle attached at one end thereof; a needle member fixed to the opposite forward end of said bar; 15 said needle member defining an open-ended enclosure having a yarn-receiving passage and a looper-receiving passage extending longitudinally therethrough, said needle member including a fabric-penetrating portion frontwardly extending in the longitudinal axis of said bar; a shuttle member mounted to said bar for reciprocating movement thereon between said handle and said needle member; an elongated looper member having one end attached to said shuttle member and the opposite forward end slidably received in said looper-receiving passage of said needle member; a presser member 20 slidably mounted to said elongated bar and extending longitudinally thereof, said presser member having a forward portion adapted to rest against the fabric to be hooked; and means for adjusting the relative position of said presser member to said bar and to said shuttle member to thereby vary the relative position of said forward end of said presser member to said forward end of said looper member whereby the penetration of the yarn in the fabric may be varied, including a coupling member in abutting engagement with 30 said presser member adjacent the rear end thereof; and releasable fastening means for fixing said coupling member to said rear portion of said presser member.

2. A hooking needle as defined in claim 1 wherein said coupling member surrounds a portion of said presser member adjacent the rear end thereof and a portion of said elongated bar.

3. A hooking needle as defined in claim 1 wherein said elongated bar includes an elongated slot disposed in an intermediate portion of said bar between said handle and said needle member; said fastening means including a screw having its treaded end extending through said slot, the opposite ends of said slot providing for the reciprocating movement of said screw in said slot.

4. A hooking needle as defined in claim 1 wherein said open-ended enclosure consists of a pair of sidewalls having lower ends fixedly attached to side edges of said forward end of said elongated bar.

5. A hooking needle as defined in claim 4 wherein the lower ends of said sidewalls are welded to said side edges of said elongated bar.

6. A hooking needle as defined in claim 1 wherein said shuttle member includes a rear leg portion and a front leg portion inter-connected by an intermediate portion extending partially over said bar; said rear leg portion having an aperture therethrough to receive said elongated bar; said front leg portion being longer than said rear leg portion and having therethrough an aperture to receive said presser member, said bar and said looper member.

7. A hooking needle as defined in claim 6 further comprising release fastening means for attaching said one end of said looper member to said shuttle member.
